UNITED STATES PATENT OFFICE

2,335,977

PLOW

Daniel W. Thomas, Richmond, Ind.

Application June 23, 1943, Serial No. 491,983

2 Claims. (Cl. 97—124)

This invention relates to plows and is designed more especially as an improvement upon the structure disclosed in Patent 1,616,398, issued to me on February 1, 1927.

In the structure disclosed in said patent a plurality of fastening means have been required for the purpose of holding together the point, the wear plate and the blade and these have frequently loosened so as to necessitate repair. Furthermore the parts have not been held together as securely as desired.

An object of the present invention is to provide a means whereby a single bolt can be employed for fastening together the point, plowshare, shearing wing or blade and landside, another single bolt being all that is required to hold these parts to the moldboard.

A further object is to provide the parts of a plow with means whereby they can interlock so as thus to be held against separation unless the main fastening means or bolt is removed.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a top plan view of a portion of a plow showing the present improvements combined therewith.

Figure 2 is a bottom plan view of the structure shown in Fig. 1.

Figure 3 is a section on line 3—3, Figure 1.

Figure 4 is a section on line 4—4, Figure 1.

Figure 5 is a section on line 5—5, Figure 1.

Figure 6 is a section on line 6—6, Figure 1.

Figure 7 is a section on line 7—7, Figure 1.

Referring to the figures by characters of reference, 1 designates a portion of a moldboard reinforced along its landside edge by a depending longitudinal rib 2 while extending into its upper surface from the opposite edge is a socket 3 opening through the bottom of a recess 4 formed in the moldboard and extending back to a shoulder 6 in the moldboard. A plowshare 7 having a landside 8 is fitted snugly upon the upper side of the moldboard against shoulder 6 and a longitudinal flange 9 is located along that side of the plowshare remote from the landside, this flange

being interrupted at the socket 3 and also terminating back from the forward end of the plowshare.

A tongue 10 extends forwardly from the landside 5 and plowshare and removably seated against the edge 11 of the plowshare and on the flange 9 is the inner or back edge portion of a cutting blade or wing 12. This blade has a tongue 13 extending laterally therefrom and adapted to be seated in the pocket 3 in the moldboard where it will be retained by the plowshare against displacement laterally. An inturned lip 3' on the moldboard laps the tongue 13 and prevents displacement outwardly in the direction of the length of the tongue.

The forward end of the blade 12 is flush with the forward end of the plowshare as will be noted by referring to Fig. 1 and these two ends are adapted to project into and be straddled by a fork 14 projecting backwardly from a point 15. The fork is formed of two oppositely disposed ears having openings 16 therein and extending into the point at one side of the ears is a socket 17 proportioned to receive the tongue 10 and fit snugly thereto. The point 15 has a wall or abutment 18 at one side of the socket 17 and between the ears constituting the fork 14 and when the point is in position engaging the plowshare 7 and the blade 12, said plowshare and the blade 15 will have their forward ends abutting against the wall so as to fit snugly. This abutment wall 18 is extended along a line which converges laterally towards the center line of the tongue 13, as will be obvious by referring for example to Figs. 1 and 2. Consequently if the tongue 13 is seated snugly in the socket 3 and the abutment wall 18 is fitted snugly against the adjacent ends of the plowshare 7 and the blade 12, said blade and plowshare cannot be separated because the walls of the socket 3 would not provide sufficient clearance for the removal of the tongue 13.

The point is adapted to be held in snug engagement with tongue 10 and the ends of the plowshare and blade by a bolt 19 inserted transversely 45 through the openings 16 and through the plowshare. With these parts all held together it becomes impossible to separate them unless the bolt is first removed. Thus the use of supplemental rivets, bolts or the like is obviated. A second bolt 20 is employed for fastening the plowshare onto the moldboard, thus maintaining it snugly thereon and against stop shoulder 6. By removing this bolt 20, the plowshare and the parts connected thereto can be instantly disconnected from the moldboard. These parts,

however, namely the plowshare 7, blade 12 and point 15, cannot be separated from one another without first removing the bolt 19.

What is claimed is:

1. The combination with a moldboard having a recess in one side edge and flanges extending from said edge, of a plowshare mounted on the moldboard and bridging the recess, a blade mounted on the flanges and bearing against the plowshare, a tongue extending from the blade and fitted snugly within the recess, said blade and plowshare having aligned forward ends, a tongue extending forwardly from the plowshare, a point having a wall abutting against the forward ends of the blade and plowshare and having a socket for the reception of the tongue on the plowshare, ears extending from the point and cooperating to constitute a fork straddling the front end portions of the blade and plowshare, and means for holding said ears securely to the plowshare thereby to maintain the point, blade and plowshare in assembled relation, that wall of the point constituting an abutment being extended along a line converging laterally toward the longitudinal axis of the tongue on the blade, 25

and means for attaching the moldboard to the plowshare.

2. The combination with a moldboard, a plowshare fastened thereto, and flanges extending laterally from the plowshare, there being a recess in the moldboard and under the plowshare intersecting the flanges, of a tongue extended forwardly from the plowshare, a blade supported by the flanges and abutting against the plowshare, 10 said blade and plowshare having aligned forward ends, a point having a fork straddling said ends of the blade and plowshare and having an abutment wall extended along a line converging laterally toward the center line of the recess in the moldboard, there being a tongue extended laterally from the blade and seated snugly in the recess, said tongue and the forward end of the blade cooperating with the walls of the recess and the abutment wall respectively to hold the 15 blade against lateral separation from the plowshare when the point is fitted against the blade and plowshare, means for securing the point to the plowshare, and a forwardly extended tongue on the plowshare removably seated in the point.

DANIEL W. THOMAS.
